W. REUSS.
PORTABLE INFANT HOUSE.
APPLICATION FILED NOV. 7, 1917.

Patented Oct. 22, 1918.

1,282,292.

UNITED STATES PATENT OFFICE.

WILHELMINA REUSS, OF CEDAR GROVE, INDIANA.

PORTABLE INFANT-HOUSE.

1,282,292.

Specification of Letters Patent. Patented Oct. 22, 1918.

Application filed November 7, 1917. Serial No. 200,819.

To all whom it may concern:

Be it known that I, WILHELMINA REUSS, a citizen of the United States, residing at Cedar Grove, in the county of Franklin and State of Indiana, have invented certain new and useful Improvements in Portable Infant-Houses, of which the following is a specification.

This invention relates to portable infant houses or pens and has as its object to provide a device of this class in which an infant may rest comfortably and will be effectually protected from drafts, domestic animals, and contact with objects which would be liable to cause injury.

Another aim of the invention is to provide a device of this class which when not in use may be arranged in compact form so as to occupy but little space, the roof of the house being formed in sections which may be swung down to serve as tables or trays upon which the infant's toys may be disposed and which, when the house is not in use, may be swung up to simulate a gable roof.

Another aim of the invention is to provide a house or pen for the purpose stated which will be constructed to support the infant above the floor surface and, consequently, out of floor drafts.

In the accompanying drawing:

Figure 1 is a perspective view of the house embodying the present invention;

Fig. 2 is a transverse sectional view therethrough.

In the drawings, the house is illustrated as comprising a substantially rectangular body including a floor or bottom 1, side walls 2, and end walls 3, the body being open at its top and being preferably supported upon springs 3' mounted upon axles 4 provided at their ends with wheels 5 so that the house or pen may be moved about from place to place. It is preferable that the house be provided interiorly with a padding or lining 6 covering the inner surfaces of the floor 1, side walls 2 and end walls 3 of the house, and serving as a cushion to protect the infant from bruises and other injuries when moving about within the house. In order to provide for ventilation of the house and thereby provide against the house becoming uncomfortably warm, one side wall 2 of the house is provided with an opening 7 covered by a screen 8.

The convertible roof of the house comprises side sections each indicated by the

numeral 9 and these sections ~~are hinged~~ connected at their inner edges to the upper edges of the side walls 2 of the house and may be swung up to form the sides of the roof shown in Fig. 2 of the drawings or swung down as shown in Fig. 1 of the drawings so as to form tables or shelves at the opposite sides of the body of the house, for the support of the infant's toys. In this latter position the sections 9 are designed to be firmly supported by means of brackets 11 which are hingedly mounted, as at 12, upon the outer faces of the side walls 2 of the house. By reference to Fig. 2 of the drawings it will be observed that the brackets may be swung to lie against the said side walls whereby to permit of the sections 9 being dropped to vertical position. In order to prevent the child's toys falling or rolling from the shelves formed by the sections 9 when they are in lowered position molding strips 13 are preferably secured upon the inner face of the sections and extend along the edges thereof. The roof also includes triangular gable sections 14 which are hinged, as at 15, at their inner edges, to the upper edges of the end walls 3 and which may be swung to upright position, as shown in Fig. 2 of the drawings, or may be swung to horizontal position, as shown in Fig. 1, to afford additional shelf or table space. When the gable sections 14 are swung to upright position, as shown in Fig. 2, their converging edges will lie inwardly of the molding strips 13 at the ends of the roof sections 9 so that the sections 14 will be prevented from accidentally dropping to horizontal position. In order to hold the sections 9 against accidental displacement when swung to the position shown in Fig. 2, latches 16 are secured upon one of the sections 9 and are engageable with keepers 17 upon the other section.

From the foregoing description of the invention it will be seen that there is provided a device of the class described which may be readily moved about from room to room, will support the infant placed therein, clear of the floor and protect it against injury, will occupy but little space when not in use, and will provide shelves or tables for the support of the infant's toys when the device is in actual use.

Having thus described the invention, what is claimed as new is:

1. A device of the class described com-

prising a body open at its top, members hingedly connected with the opposite sides of the body at the top thereof, and other members hingedly connected with the ends 5 of the body at the upper end thereof, the said members being adapted to be swung to position to serve as shelves and to be swung upwardly to simulate a roof, the last mentioned members constituting supports for 10 the first-mentioned members when the members are in swung-up position.

2. In a device of the class described, a body, shelves hingedly mounted upon the

opposite sides of the body, and shelves hingedly mounted upon the opposite ends of 15 the body, all of the said shelves being adapted to be swung down when in use and to be swung upwardly to position above the body when not in use, the first mentioned members being designed to simulate the sloping 20 sides and the last-mentioned members the sloping ends of a gable roof when all of the members are swung up.

In testimony whereof I affix my signature.

WILHELMINA REUSS. [L. s.]
